UNITED STATES PATENT OFFICE.

JORDAN L. MOTT, OF MOTT HAVEN, NEW YORK.

STOVE.

Specification of Letters Patent No. 11,999, dated November 28, 1854.

To all whom it may concern:

Be it known that I, JORDAN L. MOTT, of Mott Haven, Westchester county, New York, have invented certain Improvements in the Stove for Heating Apartments denominated the "Ovate Stove," of which the following is a full, clear, and exact description, reference being had to the accompanying drawings, making part of this specification, in which—

10 Figure 1, is an elevation; Fig. 2, a vertical section; and Fig. 3, a horizontal section taken at the line A, a, of Fig. 1.

15 The same letters indicate like parts in all the figures.

15 The body of the stove, as the title indicates, is in the general form of an egg with the larger end down and a section cut out for the grate, and connected with the base 20 by a spreading flanch cast thereon, and the upper or smaller end spread out funnel shaped, and covered with a cap plate provided with apertures, one for the smoke pipe and the other for feeding the coal and 25 provided therefor with a lid. This general form has been devised with reference to the body of coal within, for the purpose of equalizing the temperature of the outer shell, and to prevent that rapid destruction 30 of the iron which takes place in the shell of cast-iron stoves, particularly such as are not lined, where the charge of coal is placed and a little above it.

35 By the form which I have devised, the mass of metal is more nearly distributed in the proportion of the intensity of the heat from the grate to the top, and hence much less liable to be injured by unequal expansion and contraction in heating and cooling 40 than stoves as heretofore formed.

40 The grate being placed in the aperture at the large end of the ovate, the charge of coal placed thereon extends up, occupying the semi-spherical part resting on the inner 45 curved surface thereof, and hence tending constantly to descend to the grate, which being of much less area than the upper part of the charge, will prevent an intense combustion of the coal where it is in contact 50 with the shell. And from the upper surface of the charge, where the heat is most intense, the diameter gradually decreases to the top. But even when thus formed, the heat is yet too intense at the part of greatest 55 diameter, and to compensate therefor, I make this part of the stove of one or more

separate rings, each with a projecting scalloped flanch to conduct off the surplus calorific, so that the form, the separate sections, and the projecting flanch or flanches, 60 on the middle section or sections all taken in combination constitutes the novel character of my invention by which I have been able to produce a stove which, for the cost, 65 is more durable than any other known stove, and better adapted to heating apartments.

70 My invention also consists in combining with the ovate formed shell of the stove what I denominate a clothes protector, that is a hoop of much greater diameter than the shell, and provided with arms projecting inward in any ornamental form, except a continuous ring, and resting on the projecting flanch of one of the rings forming 75 the section of greatest diameter. The location of this hoop will effectually prevent clothes from coming in contact with the highly heated surface of the stove; its distance from the body of the stove will prevent it from being highly heated, and the parts which come in contact with the body of the stove being made of open work, and simply resting on the projecting flanch, will prevent it from being broken by unequal expansion.

80 In the accompanying drawings *a*, represents the base or pedestal, resting on a tripod or in any other manner. To this base is properly secured the lower flanch *b*, of the 85 lower section *c*, of the egg formed shell. The part *c*, represents the semi-spherical portion of the ovate, the lower section of which is cut out, or rather it is cast with that part open, to receive the grate *d*, which 90 is hung on a shaft *e*, the journals of which are fitted to recesses formed in the casting. One end of this shaft extends through the shell to receive a handle for turning the 95 grate, a section of the shell, as at *f*, being 100 movable for the purpose of repairs. The lower flanch *b*, spreads out from the aperture for the grate to the base plate, and constituting the ash pit with a door *g*. The upper edge of this lower section is cast with 105 a rebate to receive a ring *h*, also rebated, and cast with a projecting scalloped flanch *i*, projecting out from its outer periphery, and ornamented at the fancy of the constructor; one, two or more such rings may be placed 110 one above the other. The upper section *j*, of the shell, as before intimated, rests on the

upper ring, and the tip of this section of the ovate is also omitted, and this part is cast with a flaring flanch *k*, to which a cap plate *l*, is secured by a screw bolt *m*, running

5 down to, and through the flaring flanch.

The cap plate has two apertures, one surrounded by a collar *n*, for the smoke pipe, and the other for feeding the coal, and provided with a lip *o*, in the usual manner.

10 The clothes protector is a hoop or ring *p*, cast with open work extending inward to, and resting on, the projecting flanch of one of the rings, and at the largest diameter of the stove, to afford, by its diameter and 15 height, ample protection for the clothes of persons either standing or passing by.

I do not claim either the ovate form, the separate sections, separate rings, or extended flanches, all having been used in stoves

heretofore constructed by me, but not in 20 combination. Nor do I claim an extended rim around the stove, this having been before used at the bottom of the fretwork or outside casing of the fire pot, on line with the grate for the double purpose of securing 25 the casing and as a rest for the feet.

What I claim as my invention and desire to secure by Letters Patent is—

The extended rim or clothes protector as described, located and combined with the 30 larger diameter of the fire chamber that it may serve as a protector to prevent burning clothes, when carelessly passing, as set forth.

JORDAN L. MOTT.
